D11-160. OR D369 EX

Thomas Ball's design
for bust of Jenny Lind.
Patented April 29, 1857.—

Des. 369

Thomas Ball of Boston, Mass.
Letters Patent No. 369 Dated April 29, 1851.

The Schedule referred to in these Letters Patent and making part of the same.

To all Persons to whom these Presents, shall Come.

Be it known, that I, Thomas Ball, of Boston, in the County of Suffolk and State of Massachusetts, have produced a new design for a bust of Jenny Lind, and I do hereby declare that the following description, taken in connection with the accompanying drawings, hereinafter referred to, forms a full and exact specification of the same.

Of the drawings fig. 1 is a front view of the said new bust of Jenny Lind, and fig. 2 is a rear view of the Same.

The bust is of the cabinet size, and mounted or cast on an attic base a, a. - The drapery b, b, b, b, is arranged so as to cover one shoulder and leave the other exposed, as shown in figs 1 & 2, and the breast is covered with imitation of lace work as shown at c, c, c, c,
in fig. 1.

Having thus described my new design I shall
state my claim as follows.

That I claim in the design of a bust of Jenny-Lind of the Cabinet size as is presented in the drawings above refered to.
